UNITED STATES PATENT OFFICE.

CHRISTINE PETERSEN, OF EVANSTON, ILLINOIS.

ABDOMINAL SUPPORTER.

Application filed March 2, 1922, Serial No. 540,385. Renewed July 23, 1923.

To all whom it may concern:

Be it known that I, CHRISTINE PETERSEN, a citizen of the United States, residing at Evanston, in the county of Cook and State 5 of Illinois, have invented certain new and useful Improvements in Abdominal Supporters, of which the following is a specification.

This invention relates to abdominal supporters, and embodies a supporter which may be used in combination with a corset, or separately if desired. I am aware that it is old in this art to provide a corset with an abdominal supporter and also to provide 15 an abdominal supporter which may be used separately. Examples of the former are shown in my prior Patents Nos. 1,110,005 and 1,262,800. Much of the discomfort of prior abdominal supporters, with which I 20 am familiar, arises from the fact that they are incapable of adjustment to fit different shapes and sizes of wearers, and also contain parts which by pressure on the bony structure are uncomfortable to wear, and the 25 present improvement is the result of long experience and considerable familiarity with these garments and is designed to be free from many of the defects of the prior devices.

30 In the accompanying drawings Fig. 1 is a perspective view of the supporter used in combination with a corset. Fig. 2 is a plan showing one half or side of the supporter attached to part of a corset. Fig. 3 is a 35 side view of a modification, the supporter being used without a corset. Fig. 4 is a plan of the supporter shown in Fig. 3.

In Fig. 1, 6 indicates a corset, which may be of any suitable or desired construction, 40 adapted for the attachment of the supporter. This supporter consists of two similar parts or sections, one of which is shown in Fig. 2, each section consisting of a front piece the upper part of which, indicated at 45 7, extends above a diagonal line from the lower front corner to the upper rear corner, this part 7 being stiffened by rows of stitching or otherwise to make it relatively heavy and stiff or less flexible. A strip 8 of fabric 50 is sewed to this section, extending diagonally from the upper rear to the lower front corner, and that part of the section below the strip 8 comprises a triangular part 9 which is quite thin and flexible. But- 55 tons 10 may be attached to the lower edge of the section.

At this upper rear corner the section is attached to the sides of the corset 6 by means of straps 11 and 12, these straps being arranged at an arcuate angle to each other. The strap 11 maintains a certain amount of lift with respect to the supporter, and the strap 12 extends in a direction to bind the upper part of the supporter to the body. I have found that two straps disposed at an angle to each other are superior to a single strap.

The lower end of the section is connected to the corset by means of straps 13 and 14. Altho I prefer and have shown two of these, a single strap may be used, and these straps are connected to buckles 15 by means of which the length of the straps may be adjusted, the action being to draw in the lower end of the supporter under the abdomen with proper tension to support the abdominal organs. This adjustment is a feature of value, and will enable the device to be applied to various shapes and sizes.

When in position, the straps 13 and 14 extend or are located below the crest of the ilium, which will correspond to the space indicated at 16, and the straps 11 and 12 will extend beside the abdomen and above the iliac crest. By thus providing a supporting connection both above and below the bony projection a decidedly comfortable supporter is formed. When applied the sections are connected together by lacings 17 at the front and this permits an adjustment for size, and furthermore, the pair of sections consisting of the parts 7, 8 and 9 will lie between the iliac bones. By the means described the iliac bones are relieved of the weight or strain of supporting the 95 abdominal parts, and this weight or strain is distributed over the lower and upper portions of the back, or the back portion of the body generally as enclosed by the corset. The flexible parts 9 afford ease when sitting 100 down, since they will fold or wrinkle when the thighs are sufficiently flexed. This supporter as above described is covered by the corset when the latter is closed in the usual manner. In the modification shown in Fig. 105 4, the front parts are constructed in the same manner as above described, but instead of being attached to a corset they are attached by the straps indicated to a back consisting of two similar sections indicated 110 at 18 which are connected by lacings 19. These back sections are relatively long, to

give an extensive bearing on the back, and also to permit the location of the upper straps 11 and 12 and the lower straps 13 and 14 above and below the crest of the ilium respectively. The diagonal strips 8 give a direct support for any article which may be connected to the buttons 10.

The described supporter will be found very comfortable and has many advantages over those heretofore in use.

I claim:

1. An abdominal supporter comprising a pair of front sections fastened together, said sections being sufficiently narrow to fit between the iliac bones, and supporting straps attached to each side of said sections, some of said straps being located near the upper end of the sections, to extend above the crest of the ilium, and others being located near the lower ends of said sections, to extend below the crest of the ilium, and a strip extending diagonally from the upper rear corner to the lower front corner of each section and forming in effect a continuation

of the said straps located near the upper 25 end of the said sections.

2. An abdominal supporter comprising a pair of front sections fastened together, said sections being sufficiently narrow to fit between the iliac bones, and supporting straps 30 attached to each side of said sections, some of said straps being located near the upper end of the sections, to extend above the crest of the ilium, and others being located near the lower ends of said sections, to extend below the crest of the ilium, and a strip extending diagonally from the upper rear corner to the lower front corner of each section, that portion of each section above said 35 diagonal strap being relatively stiff, and that portion below the diagonal strip being relatively flexible.

In testimony whereof, I affix my signature in presence of two witnesses.

CHRISTINE PETERSEN.
